(57) **CLAIM**

The ornamental design for a float, as shown and described.

DESCRIPTION

FIG. 1 is a top, front, right side perspective view of a float, showing my new design; FIG. 2 is a bottom, rear, left side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of portion 9 in FIG. 1; and, FIG. 10 is an enlarged view of portion 10 in FIG. 2. The evenly dashed broken lines illustrate portions of the float. The dotted broken lines depict stitching of the float. The unevenly dashed broken lines surrounding details shown in FIGS. 1, 2, 9 and 10 are for purposes of annotating the enlarged views only and form no part of the claimed design. All the broken lines form no part of the claimed design.
